Filed Jan. 25, 1972, Ser. No. 220,722

Term of patent 14 years

Int. Cl. D8—05

U.S. Cl. D8—30

FIG. 1 is a plan view of an example of a desoldering implement or the like embodying my new design;

FIG. 2 is a side elevational view thereof showing the plunger element in an alternate position, the right side elevational features of the claimed design being substantially a mirror image of those shown in the figure; and

FIG. 3 is a bottom plan view thereof with the plunger element shown broken away for ease of illustration, its total length being approximately equal to that of said main body portions.

I claim:

The ornamental design for a desoldering implement or the like, substantially as shown and described.
